(57) **CLAIM**

The ornamental design for the reciprocating air motor, as shown and described.

DESCRIPTION

FIG. 1 is a front perspective view of a reciprocating air motor showing our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a front perspective view of another embodiment of a reciprocating air motor showing our new design;

FIG. 9 is a top plan view thereof;

FIG. 10 is a front elevation view thereof;

FIG. 11 is a right side elevation view thereof;

FIG. 12 is a rear elevation view thereof;

FIG. 13 is a left side elevation view thereof; and,

FIG. 14 is a bottom plan view thereof.

The broken lines shown represent unclaimed subject matter and form no part of the claimed design.
